United States Patent Office

Des. 203,982
Patented Mar. 8, 1966

203,982

MATHEMATICAL TEACHING DEVICE

Max J. Ruderian, 631 Wilshire Blvd.,
Santa Monica, Calif.

Filed Mar. 22, 1965, Ser. No. 84,394

Term of patent 3½ years

(Cl. D25—1)

FIG. 1

FIG. 2

FIG. 3

FIG. 4

FIG. 5

FIG. 6

FIGURE 1 is a perspective view of a mathematical teaching device showing my new design;

FIGURE 2 is a front elevational view thereof;

FIGURE 3 is a rear elevational view thereof;

FIGURE 4 is a side elevational view thereof looking from the left side of the view in FIGURE 2;

FIGURE 5 is a top plan view thereof; and

FIGURE 6 is a bottom plan view thereof.

I claim:

The ornamental design for a mathematical teaching device, substantially as shown.
